B. F. REAM, OF ADA, OHIO.

Letters Patent No. 74,721, dated February 18, 1868.

IMPROVEMENT IN SHOVEL-PLough AND CULTIVATOR.

The Schedule referred to in these Letters Patent and making part of the same.

TO ALL WHOM IT MAY CONCERN:

Be it known that I, B. F. REAM, of Ada, in the county of Hardin, and in the State of Ohio, have invented a new and improved Combined Shovel-Plough and Cultivator; and I do hereby declare that the following is a full, clear, and exact description thereof, reference being had to the annexed drawings, making part of this specification, in which—

Figures 1, 2, and 3 are plans or top views, showing respectively my improved implement arranged for a double, triple, and single-shovel plough.

Figure 4 is a side elevation of fig. 1 or 2; and

Figure 5 shows a part in detail, to be more particularly referred to hereafter.

The nature of my invention consists in so constructing the parts of a cultivator that it may be used with one, two, or three shovels, and the change of condition effected with facility, without making any material alteration in its general structure, while at the same time it will be so balanced that it will not overset when left to rest on two shovels, as seen in fig. 1—a quality which will greatly enhance the ease with which it may be worked.

In the drawings, A is the draught-beam, to which are attached the handles B B, a shovel or plough, C, and a coulter, D, when this may be deemed expedient. The front end of the draught-beam may be furnished with a clevis, if desirable, for adjusting the draught. When it is required to use two shovels, as in fig. 1, a sliding adjustable gauge-beam, E, is used. An elevation of this is shown in fig. 5. This gauge-beam has a cleft or mortise in its upper edge, in which is received the draught-beam A, to a depth nearly equal to its vertical width. The upper edge of the beam is somewhat cambered or arched, so that it is highest at its middle. A metal bar, F, bent down at its ends, as shown in fig. 5, is bolted along on the top of the beam E, in such a manner that it may be tightly held on the draught-beam A, and prevented from sliding along on it after being fixed at any point in its length. A space, equal to the thickness of the draught-beam A, is left between the ends of the gauge-beam E and the turned-down ends of the bar F. Another shovel, C', is now bolted by the front end of its draught-beam, a, to the front end of the draught-beam A, while the draught-beam a passes through and is held from lateral motion in the space between the end of the beam E and bar F. A guide-bar, G, is bolted to the other side of the front end of the draught-beam A, and its rear end, which is bent for the purpose, is engaged by the beam E and bar F, on the opposite side from the shovel C'. The front ends of the beam a of the shovel C' are held by two bolts b b, which pass through them and the beam. The coulter D, when used, may also be secured by one or both bolts b. When three shovels are wanted, it is only necessary to substitute another shovel and beam, C' a, for the guide-bar G.

The shovels may be set at any required and proper distance from each other by changing the position of the gauge-beam E on the beam A, securing it in its place by drawing down the bar F by its bolts, and loosening one and tightening the other of the bolts b b.

I claim as new, and desire to secure by Letters Patent—

The gauge-beam E, constructed substantially as described, in combination with the beams A and a, guide-bar G, shovels or ploughs C C', or any of them, and coulter D, substantially as and for the purposes set forth.

In testimony that I claim the above-described improved combined plough and cultivator, I have hereunto signed my name, this 23d day of July, A. D. 1867.

B. F. REAM.
